ATTORNEYS.

UNITED STATES PATENT OFFICE.

ALBERT BACK, OF NEW YORK, N. Y., ASSIGNOR TO THE ESTATE OF TILLIE BACK.

DESIGN FOR RUFFLING OR RUCHING.

SPECIFICATION forming part of Design No. 21,493, dated April 19 1892.

Application filed February 20, 1892. Serial No. 422,295. Term of patent 14 years.

To all whom it may concern:

Be it known that I, ALBERT BACK, a citizen of the United States, residing at New York city, in the county and State of New York, 5 have invented and produced a new and original Design for Rufflings and Ruchings, of which the following is a specification, reference being had to the accompanying drawing, forming a part thereof, which represents a side 10 elevation of a ruffling or ruching embodying the features of my design.

The design consists of a series of cup-like figures A, arranged at the edge of what appears to be a strip, their side surfaces being

in direction of the front and back of the strip, 15 and the concave surfaces of the figures all face in direction of one edge of the strip. From each cup-like figure there appears to emanate a somewhat circular figure B, and the side surfaces of the circular figures have 20 the appearance of being somewhat depressed.

I claim—

A design for a ruffling or ruching, substantially as shown and described.

ALBERT BACK.
